ATTORNEY.

UNITED STATES PATENT OFFICE

GLENN E. SMITH, OF PASADENA, CALIFORNIA

CENTRIFUGAL SWITCH

Application filed December 15, 1926. Serial No. 154,897.

My invention relates to speed warning devices designed for the purpose of indicating to the driver of a motor car when he has reached a certain speed, a warning sound being made by the device when such speed is reached. It is quite common for a driver to be absorbed in thought or to have his attention on other things and to be driving faster and faster without being conscious of the fact. It is the main purpose of my invention to provide a simple, practical and efficient device which will automatically indicate an audible sound when a given or predetermined speed has been reached so that the driver may be warned and will govern himself or herself accordingly.

Among other objects of my invention are: to provide a device which can be sold as an accessory and which can be quickly attached to a car without expensive adjustments or reconstructions; to provide a device which can be coupled into the flexible drive shaft of the speedometer without cutting the same or interfering with the efficiency of the speedometer; to provide a device which can be easily set for various speeds at which the warning sound will be given; to provide a device which will cease to give the warning sound after the predetermined speed has been reached and exceeded; and, in general, to provide an economical device which can be adjusted to any desired speed limit at which the warning is sounded and which automatically operates to draw the attention of the driver to that fact.

In order to fully explain my invention, I have shown one practical embodiment thereof on the accompanying sheet of drawings, which I will now describe.

Figure 1 is a fragmentary view of an instrument board of an automobile, with my invention shown in enlarged form, in section, to show the construction and arrangement thereof and the connection of the drive shaft; and

Figure 2 is a detail view showing the adjusting mechanism on the side of the case of the device.

Referring now in detail to the drawings, my invention as here shown for illustrative

purposes, comprises a case or housing, 1, with removable cover, 2, a shaft 3, therein, with bearings 4, at its upper end, in said cover, 2, with coupling, 5, for coupling said shaft, 3, to the shaft, 6, of a speedometer, designated, 6', and indicated in light broken lines in an instrument board, 7, also indicated in light broken lines.

On the shaft 3, within said casing, 1, is a governor, designated as a whole, 8, of well known construction, but provided with a coiled spring, 9, on said shaft, 3, the lower end of which spring bears on the collar, 10, of said governor, and the upper end of which spring bears against an adjustable collar, 11, adapted to be secured to the shaft 3, in different positions thereon for the purpose of regulating the tension of said spring, 9, and thus determining the expansion movement of said governor as it is driven by said shaft, 3. The lower end of said governor is provided with a conical or tapering member or part, 12, which moves along said shaft 3, as said governor expands and contracts, as will be understood from the drawings. The lower end of the shaft 3, is provided with a bearing, 13, in the lower end of the casing, 1, said shaft terminating in a square end, 3', for connection with a flexible shaft, designated, 14, and representing the usual speedometer drive shaft. In the present construction, the short shaft, 3, within the case, 1, is interposed into said speedometer shaft, 14, said speedometer shaft simply being pushed down sufficiently to receive the case and the shaft 3 therein. The case is held in place by means of a coupling member, or nurled collar, 15.

Mounted through a slot, 16, in the side of the case, 1, is a sleeve, 17, on a face plate, 18, and through which face plate and sleeve is a plunger rod or contact member, 19, the inner end of which extends into the path of movement of the movable part, 12, so as to be engaged thereby and moved as said movable part or member 12, moves up on said shaft 3, as will be clear. The outer end of said rod or plunger, 19, is provided with a head or contact end, 20, adapted to engage and move a spring contact, 21, and move it

into engagement with another contact member, 22, to which is connected a circuit wire, 23, leading to a buzzer, or signal device, 24, the opposite side of which is connected by 5 circuit line 25, to the ammeter, designated 26, in light lines on the instrument board, and thus completing a circuit to the ground.

The face plate, 18, is adjustable on the side of the case, 1, to move the plunger arm 10 up or down, and is secured in adjusted positions by means of thumb screws, as 27. Said face plate is preferably beveled, as at 18', and can be provided with graduations, as 28, for indicating various speeds to which it can 15 be set, so that when the motor car is driven at a speed which moves the governor sufficiently to move the plunger rod 19, it will cause the operation of the signal device, in this case being buzzer, 24.

20 Thus I have provided a very simple and accurate speed warning device including within a case a revolving shaft with governor and a movable part operated by said governor with a signal operating element 25 adapted to be engaged and moved by said part to cause the operation of the signal when a predetermined speed is reached, as indicated by said governor, and while I have shown and described one practical embodiment 30 of my invention, I am aware that changes in the details of construction and arrangement can be made without departing from the spirit of the invention, and I do not, therefore, limit my invention to the 35 showing made for illustrative purposes except as I may be limited by the hereto appended claims.

I claim:

40 In a speed warning device of the character described having a housing, a revolving governor therein with a supporting and drive shaft therefor and circuit contact elements on said housing, the combination therewith of a circuit breaker including a 45 conical member on said drive shaft and movable by said governor longitudinally on said drive shaft, a rod supported at right angles to said drive shaft and extended into the path of a part of said conical member with 50 its other end adapted to actuate said contact elements, means for adjusting said rod and contact elements together on said housing to move said rod laterally to different positions relative to said conical member, said governor being adapted to move said conical member to engage and move said rod longitudinally to actuate said contact elements.

55 Signed at Pasadena, Los Angeles county, California, this 7th day of December, 1926.
